US00D743564S

(12) **United States Design Patent** (10) **Patent No.:** **US D743,564 S**
Wathne et al. (45) **Date of Patent:** **** Nov. 17, 2015**

(54) **DRESSING**

- (71) Applicant: **Mölnlycke Health Care AB**, Göteborg (SE)
- (72) Inventors: **Christian Wathne**, Mölnlycke (SE); **Ritva Miettinen**, Skeplanda (SE); **Rose-Marie Fredrikson**, Billdal (SE); **Timo Leppänen**, Angered (SE); **Yvonne Arnkil Neselius**, Västra Frölunda (SE); **Ann-Britt Gergely**, Mölndal (SE)
- (73) Assignee: **Mölnlycke Health Care AB**, Göteborg (SE)

(**) Term: **14 Years**

(21) Appl. No.: **29/451,682**

(22) Filed: **Apr. 5, 2013**

(74) *Attorney, Agent, or Firm* — Ballard Spahr LLP

(57) **CLAIM**

The ornamental design for dressing, as shown and described.

DESCRIPTION

FIG. 1 is a top perspective view of a dressing showing our new design;

FIG. 2 is a bottom perspective view thereof;

FIG. 3 is a top plan view thereof;

FIG. 4 is a rear elevational view thereof;

FIG. 5 is a right side elevational view thereof;

FIG. 6 is a bottom plan view thereof;

FIG. 7 is a front plan view thereof; and,

FIG. 8 is a left side elevational view thereof.

In the drawings, the broken lines depict environmental subject matter only and form no part of the claim.

1 Claim, 4 Drawing Sheets
